(57) **CLAIM**

The ornamental design for a rear portion of a skid steer loader, as shown and described.

DESCRIPTION

FIG. 1 is a side view of a rear portion of a skid steer loader showing our new design;

FIG. 2 is a top left side perspective view thereof;

FIG. 3 is a top right side perspective view thereof;

FIG. 4 is a left side view thereof;

FIG. 5 is a right side view thereof;

FIG. 6 is a top plan view thereof; and,

FIG. 7 is a rear view thereof.

The broken line showing of the skid steer loader in FIG. 1 and the broken lines in FIGS. 2-7 is for illustrative purposes only and forms no part of the claimed design.

1 Claim, 6 Drawing Sheets

FIG. 2

FIG. 3

FIG. 6

FIG. 7
